UNITED STATES PATENT OFFICE.

E. W. TARPLEY, OF JACKSON, EXECUTRIX, AND J. T. SIMMS AND ISAAC HULL, OF DELTA,
MISSISSIPPI, EXECUTORS, OF C. S. TARPLEY, DECEASED.

COTTON-CLEANER.

Specification of Letters Patent No. 31,069, dated January 1, 1861.

To all whom it may concern:

Be it known that the following, taken in connection with the accompanying drawing, which forms part of this specification, is 5 such a full and clear description of the Improvement in Machinery for Cleaning Cotton, or Cotton-Whippers, invented by COLIN S. TARPLEY, late of Jackson, in the county of Hinds and State of Mississippi, de- 10 ceased, as that others will be enabled there- from to make and use the same.

Referring to the accompanying drawing, Figure 1 represents a vertical longitudinal section of a cotton cleaner or whipper con- 15 structed according to the present improve- ment; Fig. 2 a transverse vertical section thereof; Fig. 3 an end elevation, and Fig. 4 a horizontal section of the same.

In this machine, which is for extracting 20 dust and dirt from the cotton, the part marked A in the accompanying drawing represents a hopper to receive the seed cotton requiring to be cleansed.

B is the whipper chamber into which the 25 cotton passes from the hopper, and C, C' are two whippers revolving therein and situated so as to receive the cotton between them. These whippers are formed of shafts or drums armed with teeth (c c'), arranged 30 in four—more or less—rows along each shaft, at a suitable distance apart in the several rows from each other, and so that the teeth of the one whipper interlock or pass between the teeth of the adjoining 35 whipper. Both whippers (C, C') revolve in like directions simultaneously whereby their teeth interlock or pass between each other in opposite directions. This action of the whippers serves to detach much of the 40 dust dirt and trash and to divide the cotton into small locks, while breakage of parts by any coarse obstruction and injury to the fiber is avoided by the one whipper (C) driving the other (C') through a belt 45 (b) acted upon and kept at a driving ten- sion by a roller clamp or pressure bar (D) hung so as to be capable of yielding and held down to bear on the belt by a spring d. Such provision insures the uniform 50 action of the whippers under all proper or ordinary resistance but admits of slip or back action of the one whipper in case of extraordinary or improper resistance. Any

suitable driving power and means may be employed to set in motion the one whipper. 55

E, is the flue or mouth from which the cotton is delivered after being acted upon by the whippers, and F is a sieve or ribbed floor to the whipper chamber through which the dust dirt and trash that has been sepa- 60 rated from the cotton by the whippers falls, and from beneath which floor said dust dirt and trash is passed off by an inclined floor (G) to a box or other receptacle that may be emptied from time to time as needed. 65

H, is a fan set in motion by a belt (e) from the one whipper (C). This fan creates a draft or current of air from an opening or flue (I) to act upon the cotton in its descent from the whipper chamber 70 exit (E) to (say) the gin mouth, to effect more perfect clearance of dust or trash ad- 75hering to the cotton and which the whippers may have only served to loosen without de- taching but which a fan blast, thus acting upon the cotton in its free descent and after being acted upon by the whippers, effectu- 80 ally secures the separation of.

What is here claimed, as new and useful, 80 is:

The combination of the sieve floor (F), whipper chamber (B) having feed and de- 85 liver apertures substantially as described, whippers or beaters (C C'), and blast flue (I), when the latter or blast chamber is 85 separated from the dust chamber by the close partition (G), essentially as shown and described.

In testimony whereof, we have hereunto 90 subscribed our names.

ELIZA W. TARPLEY,
*Executrix of the estate of C. S. Tarpley,
deceased.*

Witnesses as to signature of Eliza W. Tarpley:

JNO. W. ROBINSON,
JOHN P. STEVENS.

J. T. SIMMS,
ISAAC HULL,
*Executors of the estate of C. S. Tarpley,
deceased.*

Witnesses as to signatures of J. T. Simms and Isaac Hull:

W. F. BOURNE,
W. A. REDFORD.
